MECHANISM FOR THE INTERCONVERSION
OF RECIPROCATION AND ROTATIONArne Feroy, New York, N. Y., assignor to Rogers
Diesel and Aircraft Corporation, New York,
N. Y., a corporation of New York

Application August 9, 1944, Serial No. 548,726

9 Claims. (Cl. 74—60)

This invention relates to mechanism for the interconversion of reciprocation and rotation for use in engines, pumps, and compressors of the class having cylinders parallel to the shaft, the class commonly called barrel type, axial, or round engine mechanisms. This invention is especially concerned with single-ended mechanisms as may be used in single-ended barrel engines, pumps, or compressors, or in each end of an opposed-piston barrel engine. This application describes further improvements in the single-ended mechanisms described in the application of E. S. Hall, Ser. No. 493,416, filed July 3, 1943 (U. S. Patent No. 2,357,735).

In such mechanisms, reciprocating members (conveniently called "recipers") may be operably connected to the shaft by means of a starplate mounted on bearings on and inclined to the shaft, the starplate having several arms, each operably connected to one of the recipers. The starplate bearings may include a journal bearing and a slipper bearing, the slippers operable upon a "slant," a plane-faced disc inclined to and rotating with the shaft, normal to and coaxial with the journal bearing.

Objects of the invention are to provide improvements in the operable mounting of the starplate on the shaft and in the operable connections between the starplate and the recipers, to facilitate production and to reduce weight and cost. Other objects are to provide a unitary or integral mounting for the starplate, with slant and shaft integral; to provide a construction by which the smaller slant member may more readily be clamped parallel to the main slant; to provide, in an opposed-piston engine mechanism, a main shaft comprising a pair of end portions each integral with its main slant and each splined to an intermediate connecting shaft, with tension means for tying the two end portions together; and to provide improved means for holding each wristpin to its starplate arm, so constructed as to permit more strength in the starplate arm while permitting axial adjustment of the wristpin on the arm.

Other objects of the invention are to form the shaft of an opposed-piston engine in three portions, the end portions each operable in a pair of main bearings supported by the frame, the bending load on the frame which is naturally rigid in bending, the center portion of the shaft serving to connect the two end portions, separately in torsion and in tension. Other objects are to form the integral shaft and slant so that the unit can be readily cast and amply strong when

cast of a high-strength cast iron or steel; and to form the starplate so that it can have adequate bending strength in the arms and torsional strength in the sections between arms when cast of high-strength cast iron or steel.

These and other objects of the invention will be more readily understood from the following description in connection with the drawings in which

- 10 Fig. 1 is a sectional elevation of the starplate mechanism at one end of an opposed-piston engine, the other end being similar with its pistons facing the pistons shown in the common cylinder block and with a common shaft member in well-known manner;
- 15 Fig. 2 is a diagrammatic view showing the manner of assembling the starplate on the unitary mounting;
- 20 Fig. 3 is an enlarged view, partly in longitudinal section and partly in elevation, of the connections between a recipper and an arm of the starplate; and
- 25 Fig. 4 is a top view of the portion of the mechanism shown in Fig. 3.
- 30 In the drawings, Fig. 1 shows a single-ended reciprocating mechanism as used at one end of an opposed-piston engine, the other end being the same, cylinder block 14 and shaft member 51 being common to both ends. Each recipper comprising a piston 18 and a crosshead 11 held together by a screw 12, the piston operable in a cylinder and the crosshead operable in a cylindrical crosshead guide 13 of larger bore than the cylinder, both formed in or supported by the frame 14 comprising the fixed parts of the machine. Several pistons 18, five or seven or another convenient number, in cylinders spaced about and parallel to the main shaft axis, are operably connected to the shaft by starplate 20.
- 35 Such a single-ended mechanism, with pistons at one end only of the crossheads, may be used in a single-ended barrel engine, pump, or compressor, or it may form half of an opposed-piston barrel engine mechanism, the other half being similar with its pistons facing pistons 18 in the same cylinders.

The main shaft connecting the two starplate mechanisms of an opposed-piston engine may include a pair of unitary shaft and slant members 30, each mounted in a pair of main bearings 40 supported by frame 14 and frame cover 16, and a connecting shaft 58 consisting of a central splined member 51 and a pair of bolts 52 with their nuts 53.

Slant member 30 has a plane-faced slant sur-

face 36 normal to the inclined axis of journal 33. Slippers 21, pivoted on starplate 20, coact with slant 31 with wedge-film lubrication. Journal bearing 23, a press fit in starplate 20, coacts with journal 33. Smaller slant 34 is bolted to main slant member 30 with its slant face parallel to slant face 31 and coacting with flange 24 of bushing 23. Smaller slant 34 also has a thrust face 35 coacting with the flange of the inner main bearing 40, locating the shaft assembly axially.

As shown in Fig. 1 and enlarged in Figs. 3 and 4, each arm of starplate 20 is operably connected to its reciprocator by a wristpin 68 and a pinhead 61. Wristpin 68 is rotatable and slidable in a bore in pinhead 61, the axis of wristpin 68 being substantially tangent to a circle concentric with and in the mid-plane of starplate 20. Pinhead 61 is rotatable and slidable in a bore in crosshead 11, the axis of the bore being substantially radial to the main shaft. The ends of wristpins 68 may be spherical as shown, to coact with internal surfaces 16 in crossheads 11, to predetermine correctly the motion of starplate 20 as described in the patent application referred to.

Wristpin 68 is milled out to fit the hook on the arm of starplate 20, and is held in engagement with the hook by wedges 62. The milled recess in wristpin 68 is made longer than the width of the arm of starplate 20, to permit axial adjustment of wristpin 68 relative to the arm. Axial adjustment of wristpin 68 may be made by loosening one of the wedges 62 while driving the other deeper. Either wedge tightly driven locks both, and secures wristpin 68 in engagement with the hook of the arm of starplate 20. Tapped holes are provided in wedges 62 to aid in withdrawing them. Lock plate 63 is held down on wedges 62 by screws 64 to safety them in their final adjustment.

To assemble the mechanism, intermediate shaft 51 is placed in position, temporarily supported on flanges 15 of frame 14. Pistons 10 may be entered in the cylinders with their rings in place. Unitary slant and shaft 30 is deformed at 32 to permit starplate 20 with its bushing 23 to be swung into alignment for engagement with journal 33, as indicated in Fig. 2. When starplate 20 with its slippers 21 and bushing 23 has been assembled on slant unit 30, and the smaller slant 34 bolted thereto, the whole starplate and slant assembly as a unit, with a crosshead 11 loosely surrounding each arm, may be entered in the end of frame 14, the inner end of unitary shaft 30 entering bearing 40 and engaging the splines 55 on intermediate shaft 51. Then cover 16 may be put in place, the other bearing 40 supporting unitary shaft 30; bolt 52 may be screwed into the end of intermediate shaft 51, and drawn up by nut 53 until the running parts are properly positioned relative to frame 14, after which nut 53 may be locked; and pistons 10 may be fastened to each crosshead 11 by screw 12, the screw being locked by a slug of soft metal 18, driven in and upset against the knurled head of screw 12, as shown in Fig. 3.

With each arm of starplate 20, in turn, inclined toward cover 16, its pinhead 61 and wristpin 68 may be inserted in its crosshead 11; then conveniently at mid-stroke position, wristpin 68 may be locked in correct position on its arm by wedges 62 and lock plate 63 as described.

In operation, reciprocation of the reciprocators comprising pistons and crossheads, is accompanied by rotation of shaft 50, by the operable connection of

the starplate mechanism, in well-known manner. Oil fed into shaft 50 flows outwardly to starplate 20, lubricating slippers 21 and the other bearings; and thru the arms of starplate 20, wristpins 68 and pinheads 61, to lubricate their bearing surfaces, thence into pistons 10 to aid in cooling them, from which it returns to the casing.

It is understood that the invention is capable of modification and that changes may be made in the construction and in the arrangement of the various parts without departing from the spirit or scope of the invention, as expressed in the following claims.

I claim:

15. In an opposed-piston engine mechanism having a pair of starplate mechanisms and intermediate shaft means connecting them together; a starplate mechanism comprising reciprocating members parallel to the axis of rotation of said shaft means and each including a piston and a crosshead, a starplate, a mounting for said starplate including integral slant and shaft portions, and operable connections between the starplate and its reciprocating members; each of said connections including an arm on said starplate, a wristpin substantially tangent to a circle in the midplane of said starplate, a pair of wedges adjustably fixing said wristpin to said arm, means for locking said wedges, and a pinhead operably receiving said wristpin and operable in a bore in the crosshead of its reciprocating member, the axis of said bore being substantially radial to said shaft axis, the ends of said wristpin coacting with said crosshead to aid in controlling correctly the motion of said starplate.
20. In an opposed-piston engine mechanism having a pair of starplate mechanisms and an intermediate shaft connecting them together; a starplate mechanism comprising reciprocating members parallel to said shaft, a starplate, an integral mounting for said starplate including slant and shaft portions, and operable connections between the starplate and its reciprocating members, each of said connections including an arm on said starplate, two plane faces on said arm and a wristpin formed to engage said plane faces, the angle between each of said plane faces and the plane of said starplate being greater than the angle between the plane of said starplate and a plane normal to said shaft, and a pair of wedges holding said wristpin in engagement with said plane faces.
25. In a machine of the class described, a shaft, cylinders parallel thereto, reciprocating members operable in said cylinders, and mechanism operably connecting said reciprocating members to said shaft, said mechanism including a starplate operably connected to said reciprocating members and operably mounted upon said shaft, the operable connection between said starplate and each reciprocating member including an arm on said starplate, a wristpin, and wedges holding said wristpin against said arm.
30. In a machine of the class described, a shaft, cylinders parallel thereto, reciprocating members operable in said cylinders and each including a crosshead portion and a piston portion at one end of said crosshead portion, a starplate operably mounted on and inclined to said shaft, an arm on said starplate for each of said reciprocating members, a wristpin pressed against the piston side of said arm by the driving forces of said piston portion, and a pair of wedges one on each side of said arm securing said wristpin to said arm.
35. In a machine of the class described, a shaft, cylinders parallel thereto, reciprocating members operable in said cylinders and each including a crosshead portion and a piston portion at one end of said crosshead portion, a starplate operably mounted on and inclined to said shaft, an arm on said starplate for each of said reciprocating members, a wristpin pressed against the piston side of said arm by the driving forces of said piston portion, and a pair of wedges one on each side of said arm securing said wristpin to said arm.
40. In a machine of the class described, a shaft, cylinders parallel thereto, reciprocating members operable in said cylinders and each including a crosshead portion and a piston portion at one end of said crosshead portion, a starplate operably mounted on and inclined to said shaft, an arm on said starplate for each of said reciprocating members, a wristpin pressed against the piston side of said arm by the driving forces of said piston portion, and a pair of wedges one on each side of said arm securing said wristpin to said arm.
45. In a machine of the class described, a shaft, cylinders parallel thereto, reciprocating members operable in said cylinders and each including a crosshead portion and a piston portion at one end of said crosshead portion, a starplate operably mounted on and inclined to said shaft, an arm on said starplate for each of said reciprocating members, a wristpin pressed against the piston side of said arm by the driving forces of said piston portion, and a pair of wedges one on each side of said arm securing said wristpin to said arm.
50. In a machine of the class described, a shaft, cylinders parallel thereto, reciprocating members operable in said cylinders and each including a crosshead portion and a piston portion at one end of said crosshead portion, a starplate operably mounted on and inclined to said shaft, an arm on said starplate for each of said reciprocating members, a wristpin pressed against the piston side of said arm by the driving forces of said piston portion, and a pair of wedges one on each side of said arm securing said wristpin to said arm.
55. In a machine of the class described, a shaft, cylinders parallel thereto, reciprocating members operable in said cylinders and each including a crosshead portion and a piston portion at one end of said crosshead portion, a starplate operably mounted on and inclined to said shaft, an arm on said starplate for each of said reciprocating members, a wristpin pressed against the piston side of said arm by the driving forces of said piston portion, and a pair of wedges one on each side of said arm securing said wristpin to said arm.
60. In a machine of the class described, a shaft, cylinders parallel thereto, reciprocating members operable in said cylinders and each including a crosshead portion and a piston portion at one end of said crosshead portion, a starplate operably mounted on and inclined to said shaft, an arm on said starplate for each of said reciprocating members, a wristpin pressed against the piston side of said arm by the driving forces of said piston portion, and a pair of wedges one on each side of said arm securing said wristpin to said arm.
65. In a machine of the class described, a shaft, cylinders parallel thereto, reciprocating members operable in said cylinders and each including a crosshead portion and a piston portion at one end of said crosshead portion, a starplate operably mounted on and inclined to said shaft, an arm on said starplate for each of said reciprocating members, a wristpin pressed against the piston side of said arm by the driving forces of said piston portion, and a pair of wedges one on each side of said arm securing said wristpin to said arm.
70. In a machine of the class described, a shaft, cylinders parallel thereto, reciprocating members operable in said cylinders and each including a crosshead portion and a piston portion at one end of said crosshead portion, a starplate operably mounted on and inclined to said shaft, an arm on said starplate for each of said reciprocating members, a wristpin pressed against the piston side of said arm by the driving forces of said piston portion, and a pair of wedges one on each side of said arm securing said wristpin to said arm.
75. In a machine of the class described, a shaft, cylinders parallel thereto, reciprocating members operable in said cylinders and each including a crosshead portion and a piston portion at one end of said crosshead portion, a starplate operably mounted on and inclined to said shaft, an arm on said starplate for each of said reciprocating members, a wristpin pressed against the piston side of said arm by the driving forces of said piston portion, and a pair of wedges one on each side of said arm securing said wristpin to said arm.

5. In mechanism of the character described, a shaft, a starplate operably mounted on and inclined thereto, a reciprocating member movable on an axis parallel to said shaft, an arm on said starplate, and a wristpin mounted on said arm with limited axial adjustability and operably connected to said reciprocating member, and a pair of wedges holding said wristpin to said arm, said wristpin adjustable axially by withdrawing one wedge and driving the other deeper.

6. A starplate mechanism comprising a shaft, a starplate operably connected to said shaft, a reciprocating member operating in a path parallel to said shaft, an arm on said starplate, a wristpin operably connected to said reciprocating member and having a recess formed therein to receive said arm, holes formed partly in the sides of said arm and partly in the ends of said recess, and wedges in said holes for securing said arm to said wristpin.

7. A starplate mechanism comprising a shaft, a starplate operably connected to said shaft, a reciprocating member operating parallel to said shaft, an arm on said starplate, a wristpin operably connected to said reciprocating member, said wristpin having a recess to receive said arm, wedge receiving holes formed partly in the sides of said arm and partly in the ends of said recess, and wedges in said holes, said holes and wedges being so formed and arranged that the setting of said wedges draws said wristpin and arm together and the loosening of one wedge and the tightening of the other wedge may effect a relative adjustment between said arm and wristpin longitudinally of said wristpin.

8. In an opposed-piston engine mechanism of

the barrel type having a frame and cylinders spaced about and parallel to the main axis thereof: a pair of piston members operably opposed in each of said cylinders; a pair of starplates 5 operably connected to said piston members; a pair of integral slant and shaft members, one for each starplate, each including bearing means operably mounting a starplate on an axis inclined to said main axis and bearing means for supporting said integral member for rotation in said frame on said main axis; and shaft means connecting said integral members, said shaft means including a splined shaft connecting said integral members in fixed position rotationally relative to each other and drawbolts holding said integral members in fixed position axially relative to each other and to said splined shaft.

9. A mechanism comprising a frame, cylinders spaced about and parallel to the main axis of said frame, reciprocating members operable in said cylinders, a starplate, operable connections between said starplate and said reciprocating members, and an operable mounting for said starplate comprising an integral shaft and slant member, bearings for the shaft of said member in and coaxial with said frame, a journal and a slant face integral with said member and operably supporting said starplate with its axis inclined to that of the shaft of said member, and 20 a smaller slant member clamped to said integral shaft and slant member with its slant face parallel to the slant face of said member.

ARNE FEROY.
